UNITED STATES PATENT OFFICE.

THOMAS BOWER, OF HULL, ROBERT WILLIAM BOWER, OF LEEDS, AND JAMES BLACKBURN, OF WOODLESFORD, COUNTY OF YORK, ENGLAND.

MACHINE FOR CUTTING COAL.

SPECIFICATION forming part of Letters Patent No. 399,485, dated March 12, 1889.

Application filed July 5, 1888. Serial No. 279,145. (No model.) Patented in England May 26, 1887, No. 7,662, and December 9, 1887, No. 16,955.

To all whom it may concern:

Be it known that we, THOMAS BOWER, ROBERT WILLIAM BOWER, and JAMES BLACKBURN, of Hull, Leeds, and Woodlesford, respectively, all in the county of York, England, have invented new and useful Improvements in Machines or Apparatus for Cutting Coal, (for certain of which improvements a patent was granted to us and to Frederick Mori in Great Britain, dated May 26, 1887, No. 7,662, and for certain other of which improvements a patent was granted to us in Great Britain, dated December 9, 1887, No. 16,955,) of which the following is a full, clear, and exact description.

The object of our invention is to improve the construction of the cutters employed for cutting coal, and also refers to the employment of an electric motor for imparting motion to the same.

In the accompanying drawings, Figure 1 is a longitudinal section of cutter. Fig. 2 is a side elevation, and Fig. 3 a plan, looking at the top, showing cutters attached to motor-shaft direct.

We construct the cutters in such a form that they can be more readily withdrawn from the work, at the same time causing less waste of coal during the cutting operation. For these purposes we make the cutter-bar A of a taper form toward its outer extremity. The cutters B, also, which we employ are gradually reduced in size, assuming, also, a taper form, as shown in the accompanying drawings. The base of the cutters B may be of a polygonal form, as shown, and into these are screwed or otherwise fastened diamond-shaped or pointed steel bits c, or such steel bits may be cast in one with the polygonal cutters.

By these improvements not only is the cut or opening made in the coal of a less area, but also the slightest movement of the cutters releases them from the surface. We would have it understood that the aforesaid taper cutter-bar and cutters are equally applicable to other coal-cutting apparatus having similar motions to those hereinafter described.

Hitherto when electricity has been employed

for imparting motion for the purpose of cutting coal the motor has been constructed separate and distinct from the coal-cutting machine, and the machine has been so constructed that the motor could either be placed thereon and engage therewith by means of suitable gearing or wheels through which the required motion is transmitted to the machine, or the motor, when preferred, could be placed at any suitable distance from the machine and motion transmitted to such machine by rope, belt, or other ordinary means.

Now in our improvements we dispense with the coal-cutting machine hitherto employed, and impart the required rotary motion to the cutter-bar direct from the motor-shaft, saving thereby considerable expense. At the same time the work is quicker and more perfectly accomplished.

In the drawings, at Figs. 2 and 3, we have shown an "Immissch" motor, D, mounted on a turn-table, E, carried on the bed-plate F, the whole being mounted upon wheels or runners G. The motor-shaft H has provided on the end of it a coupling-plate, I, corresponding with another coupling-plate, J, provided on the cutter-bar or shaft A. The shaft A or bar containing the cutters B is coupled to the motor-shaft H by means of the aforesaid coupling-plates I and J and bolts K, or by other suitable means. The required rotary movement is given to the turn-table E, on which the motor D rests, by means of a worm, L, mounted on a shaft, M, supported in bearings N on the bed-plate F and worm-wheel segment O, provided on the rim of the turn-table E. By this means the cutter-bar can be moved along by the attendant as the coal is being cut and the proper feed given thereto.

Ordinary means are employed for regulating the speed of the motor for the purpose of varying or adjusting the speed of the cutter-bar.

Although we have shown our improvements applied to an Immisch motor, we would have it understood that they are also applicable to other electric motors having a similar rotary motion.

We claim as our invention—

1. In a machine for cutting coal, a cutter consisting of a tapering bar, A, provided with cutters or pieces B, of polygonal form, having diamond-shaped or pyramidal steel bits C secured thereto, substantially as and for the purpose herein described.
  2. In a machine for cutting coal, the combination, with the tapering cutter bar or shaft A, provided with the coupling-plate J, of the motor D, having its shaft H provided with the coupling-plate I, whereby motion is transmitted direct from the motor-shaft, substantially as herein described.
  3. In a mining-machine, the combination, with a laterally-moving carriage, of an electric motor mounted thereon, and a cutter-bar
- in line with, carried by, and forming a continuation of the armature-shaft, substantially as set forth.
4. In a mining-machine, a taper cutter-bar 20 polygonal in cross-section, in combination with a series of removable cutters, B, correspondingly tapered and adapted to fit over and be rotated by said taper bar, and provided with diamond-shaped pointed steel projections, substantially as set forth.

THOMAS BOWER.

ROBERT WILLIAM BOWER.

JAMES BLACKBURN.
